(57) **CLAIM**

The ornamental design for a first aid kit container, as shown and described.

DESCRIPTION

FIG. 1 is an isometric view from above and one side of a first embodiment showing my new design;

FIG. 2 is another isometric view, from below and one side;

FIG. 3 is a front elevation view, the opposite rear elevation view being a mirror thereof;

FIG. 4 is a side elevation view, the opposite side elevation view being a mirror thereof;

FIG. 5 is a plan view;

FIG. 6 is an isometric view from above and one side of a second embodiment showing my new design;

FIG. 7 is another isometric view, from below and one side;

FIG. 8 is a front elevation view, the opposite rear elevation view being a mirror thereof;

FIG. 9 is a side elevation view, the opposite side elevation view being a mirror thereof;

FIG. 10 is a plan view;

FIG. 11 is an isometric view from above and one side of a third embodiment showing my new design;

FIG. 12 is another isometric view, from below and one side;

FIG. 13 is a front elevation view, the opposite rear elevation view being a mirror thereof;

FIG. 14 is a side elevation view, the opposite side elevation view being a mirror thereof; and,

FIG. 15 is a plan view.
